MAGNETIC FLUID BRAKE

Filed March 22, 1949

FIG. 1

UNITED STATES PATENT OFFICE

2,607,542

MAGNETIC FLUID BRAKE

Gordon C. Spillman, Roselle, N. J., assignor to
Western Electric Company, Incorporated, New
York, N. Y., a corporation of New York

Application March 22, 1949, Serial No. 82,808

5 Claims. (Cl. 242—45)

1

This invention relates to a wire tensioning apparatus and method and more particularly to apparatus wherein the wire tension is controlled by variations in a magnetic field.

In cable stranding, which is one main application of the present invention, a plurality of wires, in the number required for a given cable, are passed from their individual reels through apertures in a wire grouping face plate and then through stranding apparatus to a take-up unit which supplies the tension for pulling the wires from their respective reels. In such machines it is important to regulate the tension to a close degree to avoid breaking the wire and to prevent irregularities in the lay of the wires in the cable.

In one well known tension regulating device a jockey arm, which is actuated by the variations in wire tension, varies the drag produced on the reel by a friction type brake. As in any brake of this general type, the constant frictional engagement and disengagement of the brake elements cause a wear and tear that requires frequent replacement and presents a serious problem of maintenance.

It is an object of this invention to improve the regulation of tensioning apparatus so that it may be operated for long periods without replacement or loss of time for repairs.

In one embodiment of the invention, oil or other liquid having magnetic particles suspended therein is circulated in a closed circuit by a pump driven by a wire reel as the reel feeds wire into a stranding machine. At a suitable point in the closed circuit the liquid passes through a magnetic field whose strength is varied by variations in the wire tension, as for example by means of a conventional jockey arm. The magnetic particles, when passing through the magnetic field, tend to align themselves with it thereby partially solidifying the suspension. The strength of the magnetic field controls the degree of solidification which in turn controls the load on the pump and thereby the speed of the reel.

The use of magnetic fluid suspensions in fluid clutches with an adjustable magnetic field to control the degree of solidification has been proposed heretofore, and is discussed by Jacob Rabinow in the National Bureau of Standards Technical News Bulletin of May, 1948. Applicant therefore is not claiming the basic idea but does claim the improvement represented by the present invention.

Other objects and advantages will be apparent from the following detailed specification when taken in conjunction with the attached drawing in which:

Fig. 1 is a side elevational view of the invention;
Fig. 2 is a plan view of the invention;
Fig. 3 is a sectional view of a device which aids in maintaining the wire at a desired tension.

5 With reference to the drawing, a reel 11 is mounted between centering supports 12 and 13. Centering support 12 is positioned on shaft 14 of pump 15, the pump being supported by base plate 22, and utilizes a spring 16 to urge its inclined surface into a frictional fit with the reel 11. Rigidly mounted on the pump shaft 14 is a supporting plate 21 having two counterbalancing lugs 17, one of which has a pin (not shown) which engages a corresponding hole in reel 11 to form a driving connection between the reel and the pump. Centering support 13 is located on bracket 18, and is provided with a lever 19 which coacts with the inclined surface 20 to lock the reel into position, and also to provide a rapid unlocking means.

10 The reel 11 has wound on it a given length of wire 24. After the reel has been placed in position one end 25 of the wire is passed over a roller 26, mounted on supports 27, and then around a pulley 28 of a conventional jockey arm 29. After leaving the pulley 28 the wire is fed along with the other wires which are to form the cable through a positioning plate (not shown) and into a stranding apparatus.

15 The pump 15 has a closed circuit consisting of pipes 33 and suitable connections 34. Contained in the pipe circuit is a quantity of oil or other similar liquid which has suspended in it finely divided particles having magnetic properties, which combine with the liquid to form a magnetic fluid suspension.

20 Encircling one section of pipe 33 is a coil 35 formed of conductive wire which is wound on a spool 36. Terminals 37 correspond to the two opposite ends of the coil and these terminals are connected through leads 38 to terminals 39 of a rheostat 40. A battery 41 is connected in one of the leads 38 to provide a source of potential for the coil 35.

25 The rheostat 40 has a tubular extension 42 which is threaded through a hole in bracket 43 and held in place by nuts 44. The movable element 45 of the rheostat is mounted on shaft 46 which is positioned within the tubular extension 42, and held in place at its upper end by housing 47. Mounted on the shaft 46 is a disc 48 having the jockey arm 29 rigidly connected thereto, so that the disc and shaft are caused to rotate by any movement of the arm along the path of wire feed.

30 With reference to Figure 3, a rod 53 is mounted

on the same rheostat shaft 46 as the arm 29 and any movement of the arm 29 is duplicated by the rod 53. Two shafts 54, positioned in cylindrical openings 51, have enlarged portions 52 which bear on the rod 53 from opposite sides, being urged against the rod by springs 56. These springs are held in place at one end by plugs 57 which are screwed into the openings 51. By varying the position of these plugs, it is possible to vary the position at which it is desired to maintain the rod 53.

When the coil 35 is energized, a magnetic field is set up through that part of the magnetic fluid suspension in the pump circuit which is in the vicinity of the coil. This causes the particles 15 in the suspension to align themselves in the magnetic field, and thus tend to solidify that part of the suspension affected by the magnetic field. This solidification, which amounts to a local increase in the viscosity of the fluid suspension, increases the load on the pump 15 and causes it to act as a brake on the reel 11 which drives it.

By varying the current through the coil 35 the degree of solidification of the suspension and thereby the pressure against which the pump 20 must operate may be varied. This variation affords a means of control of the speed of the reel 11 and accordingly control of the tension in the wire 25. Automatic regulation of the wire 25 tension is attained by using the jockey arm 29, whose movements along the path of the wire is directly controlled by the wire tension, to vary the resistance of the rheostat 40 and thus the current passing through the coil. If the wire 30 tension gets too low, the jockey arm will move in a direction opposite to that in which the wire is fed into the stranding apparatus. This movement rotates the disc 48 which turns the shaft 46 on which the movable element of the rheostat is mounted so that the resistance of the coil circuit is reduced. This will increase the coil current, which will increase the degree of solidification of the magnetic fluid suspension and cause the wire tension to increase to a normal desired value as a result of the reduced reel rotation caused by the increased load on the pump.

When the wire tension becomes too high, the jockey arm will be pulled in the direction in which the wire is being fed into the stranding apparatus. The resultant rotation of the disc 48 will turn the movable element of the rheostat in a direction which will increase the resistance of the coil circuit. The coil current and the degree of solidification of the suspension will then decrease and lighten the load against which the pump operates. This allows the reel 11 to increase in speed and so reduces the wire tension.

The spring 56 on the side of the rod 53 corresponding to the direction of wire feed, causes the jockey arm to seek a position where the compression on the spring equals the pull on the jockey arm caused by the feeding of the wire. The two springs 56 also act to limit the total distance which the jockey arm may travel, and aid the rheostat action in providing a smooth regulation of the desired tension.

It is a simple matter of adjustment to coordinate the allowable movement of the jockey arm with the rheostat settings to provide a smooth and automatic regulation of the wire tension.

One practical advantage of the proposed apparatus is that when it is desired to stop the stranding process for any reason, the increased loading on the pump caused by the resultant movement of the jockey arm will cause the wires 75

at rest to remain under tension by acting as a brake on the reel and preventing the loss of tension which would occur if the reel were free to turn.

By using the invention herein described it is possible to maintain a uniform wire tension with apparatus that is simple in operation and which requires a minimum of maintenance due to the almost complete absence of frictionally engaging parts.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. In a wire tension regulating device, the combination with a rotatable reel of wire and means for rotating the reel by withdrawing wire from it, of a closed path containing magnetic particles suspended in a liquid, a pump driven by rotation of the reel for circulating the liquid in the path, and means controlled by the tension in the wire for varying the speed of the reel by varying the viscosity of the liquid suspension circulated by the pump.

2. In a wire tension regulating device, the combination with a rotatable reel of wire and means for rotating the reel by withdrawing wire from it, of a closed path containing magnetic particles suspended in a liquid, a pump driven by rotation of the reel for circulating the liquid in the path, means for subjecting the liquid to the action of a magnetic field, and means controlled by the tension in the wire for varying the speed of the reel by varying the strength of the magnetic field.

3. In a wire tension regulating device the combination with a rotatable reel of wire, means for rotating the reel by withdrawing wire from it, and a member varying in position with the changes in tension in the wire being withdrawn, of a closed path containing magnetic particles suspended in a liquid, a pump driven by rotation of the reel for circulating the liquid in the path, means for subjecting the liquid to the action of a magnetic field and means controlled by the member for varying the speed of the reel by varying the strength of the magnetic field.

4. In a wire tension regulating device, the combination with a rotatable reel of wire and means for rotating the reel by withdrawing wire from it, of a closed path containing magnetic particles suspended in a liquid, a pump driven by rotation of the reel for circulating the liquid in the path, and means for varying the speed of the reel by varying the viscosity of the liquid suspension circulated by the pump, said means comprising a coil of conductive wire in proximity to the closed path, an energizing circuit for the coil, and means for varying the current passing through the coil.

5. In a wire tension regulating device the combination with a rotatable reel of wire, means for rotating the reel by withdrawing wire from it, and an arm varying in position with the changes in tension in the wire being withdrawn, of a closed path containing magnetic particles suspended in a liquid, a pump driven by rotation of the reel for circulating the liquid in the path, means including a coil of conductive wire and an energizing circuit for said coil for subjecting the liquid to the action of a magnetic field, and

5

a variable resistance connected in the coil energizing circuit for varying the strength of the field, said resistance being controlled by movement of the arm.
